UNITED STATES PATENT OFFICE

92,791

DESIGN FOR AN ERASURE GUARD RULE

Ralph L. Burgess, Denver, Colo., assignor to Brown
& Bigelow, St. Paul, Minn., a corporation of
Minnesota

Application April 30, 1934, Serial No. 51,583

Term of patent 3½ years

To all whom it may concern:

Be it known that I, RALPH L. BURGESS, a citizen
of the United States, residing at Denver, county
of Denver and State of Colorado, have invented a
new, original and ornamental Design for an
Erasure Guard Rule, of which the following is a
specification, reference being had to the accom-
panying drawing forming part thereof:

The figure is a face view of an erasure guard
rule showing my new design.

I claim:

The ornamental design for an erasure guard
rule as shown.

RALPH L. BURGESS.
